(57) **CLAIM**

The ornamental design for an embossed, non-woven fabric, as shown and described.

DESCRIPTION

FIG. 1 is a top, plan view of a portion of an embossed, non-woven fabric showing our new design; and, FIG. 2 is a perspective view thereof, as seen from a top, side vantage.

FIG. 1 and 2 show a portion of the embossed, non-woven fabric, which extends indeterminately in length and in width, and which shows an embossed, repeating pattern. The bottom of the embossed, non-woven fabric is non-ornamental and does not form a part of our new design.
